BUTTON

Filed Feb. 23, 1929

UNITED STATES PATENT OFFICE

CHARLES H. MILLER, OF DETROIT, MICHIGAN

BUTTON

Application filed February 23, 1929. Serial No. 342,062.

My invention relates to a new and useful improvement in a button and has for its object the provision of a button which may be easily and quickly attached to and detached from a garment.

Another object of the invention is the provision of a button having attaching means whereby the button may be easily and quickly attached to a garment and so arranged and constructed that the attaching means may be locked in position.

Another object of the invention is the provision of a button having attaching means of this class so arranged and constructed as to be simple of structure, economical of manufacture, durable and highly efficient in use.

Other objects will appear hereinafter.

The invention consists in the combination and arrangement of parts hereinafter described and claimed.

The invention will be best understood by a reference to the accompanying drawings which form a part of this specification, and in which,

Fig. 1 is a rear elevational view of the invention.

Fig. 2 is a sectional view taken on line 2—2 of Fig. 1.

Fig. 3 is a fragmentary sectional view taken on line 3—3 of Fig. 1.

Fig. 4 is a central sectional view of a modified form of the invention.

Fig. 5 is a perspective view of the fastening device used with the invention.

Fig. 6 is a rear elevational view of a further modified form of the invention.

Fig. 7 is a central sectional view of the form shown in Fig. 6.

Fig. 8 is a rear elevational view of a further modified form of the invention.

Fig. 9 is a central sectional view of the form shown in Fig. 8.

Fig. 10 is an elevational view of a further modified form of the invention with parts broken away.

Fig. 11 is a view taken on line 11—11 of Fig. 10.

Fig. 12 is a side elevational view with parts broken away and parts shown in section of a further modified form of the invention.

Fig. 13 is a perspective view of a modified form of the invention.

In the form shown in Fig. 1, the button 18 may be formed from metal or molded from any suitable material.

It is provided on its rear side with a recess 19 into which a fold 20 of the fabric upon which it is to be fastened is inserted. A socket 21 communicates with a recess 19 and is in alignment with the

passage 22 which communicates the recess 19 with a recess 23.

This recess communicates with a recess 24 by a passage 25.

After the fabric is inserted in the recess 19 a fastening member 26, which is in the nature of a pin, is inserted down the passage 22 through the

fabric and into the socket 21. An angularly turned locking portion 27 is formed on the

end of the pin 26 and adapted to be snapped into the passage 25.

The surface 28 which forms the bottom of the recesses 23 and 24

is extended at right angles to the axis of the pin 26 but the angularly turned portion 27 is inclined to this axis so that when it is

pressed into the passage or groove 25, a

springing of the angularly turned portion 27 is effected, thus securely locking the pin

in position and preventing its undue rotation from its axis.

The recess 24 is sufficiently large to permit the engagement of

a body behind the portion 27 when it is de-

sired to remove the button from the garment on which it is mounted.

In Fig. 4, I have shown a slightly modified form of the invention in which a disc 29 is

provided with a prong 30 having an eyelet 31 formed therein and this prong may be pro-

jected through an opening 32 formed in the

garment 33, so that the prong 30 projects into

the recess 19. The pin 26 is then projected

through the eyelet of the prong 30 so as to

secure the button on the garment 33.

In the form shown in Figs. 6 and 7, I have

provided the pin 26 with a knurled head 33

and a threaded portion 34 so that after the

pin 26 is projected through the fabric or

through the prong 30, the same may be

locked in position by threading the part 34

into the recess formed in the abutment itself.

In Fig. 8, I have illustrated the invention

100

which a cut-away portion 35 serves to permit the passage of the fabric into the path of the pin 26.

In Fig. 10, I have illustrated the invention adapted for use as a safety pin. In this form a head 36 is connected by a wire 37 to a head 38, the head 36 having the recesses 23' and 24' connected by a suitable passage to accommodate the angularly turned portion 10 27' of the pin 26 which is adapted to engage in the socket 21' formed in the head 38.

In the form shown in Fig. 12, the head 36 is connected by the wire 37 to the head 38 and the pin 26 is provided with a knurled head 38 15 and a threaded portion 40 for threading into the head 36.

With a button or fastening device constructed in this manner, it is evident that a secure fastening of the device in position on 20 a garment may be effected without requiring any stitching or sewing. It is believed evident that a removal and replacement of the button may be easily and quickly effected.

In the form shown in Fig. 13, I have indicated a button forming plate 43 on which is mounted a block 44 in which are provided the recesses 45 and 46. A block 47 is mounted on the plate 43 in which is formed a slot for 25 reception of the end of the pin 26. This 30 form of fastener lends itself particularly to its use on a badge or the like.

In the appended claims, the term button is used to indicate, where the terminology will 35 permit, the spaced apart heads 36 and 38 as well as other suitable fastening devices to which the invention may be utilized and the use of which would readily be suggested.

While I have illustrated and described the 40 preferred form of my invention, I do not wish to limit myself to the precise detail of structure shown but desire to avail myself of such variations and modifications as come 45 within the scope of the appended claims.

Having thus described my invention, what 45 I claim as new and desire to secure by Letters Patent is:

1. A button of the class described having a recess formed in one of its faces communicating at one side with a socket and at the other side with a passage, said passage communicating with a recess on said face, said second mentioned recess communicating through a passage with another recess on said face; a pin projected through said first mentioned passage and engageable in said socket.

2. A button of the class described having a recess formed in one of its faces communicating at one side with a socket and at the other side with a passage, said passage communicating with a recess, said second mentioned recess communicating through a passage with another recess; a pin projected through said first mentioned passage and engageable in said socket; and means for lock-

ing said pin against removal from said passage.

3. A button of the class described having a recess formed in one of its faces communicating at one side with a socket and at the other side with a passage, said passage communicating with a recess, said second mentioned recess communicating through a passage with another recess; a pin projected through said first mentioned passage and engageable in said socket; an angularly turned portion on said pin adapted for engaging in said second mentioned passage for locking said pin against removal from said first mentioned recess.

4. A button of the class described having a recess formed in one of its faces communicating at one side with a socket and at the other side with a passage, said passage communicating with a recess, said second mentioned recess communicating through a passage with another recess; a pin projected through said first mentioned passage and engageable in said socket; an angularly turned portion on said pin adapted for engaging in said second mentioned passage for locking said pin against removal from said first mentioned recess, said angularly turned portion upon engagement in said second mentioned recess being sprung from normal position.

In testimony whereof I have signed the foregoing specification.

CHARLES H. MILLER.
